UNITED STATES PATENT OFFICE.

HERMAN M. HOELSCHER, OF CHICAGO, ILLINOIS, ASSIGNOR TO L. WOLFF MANUFACTURING COMPANY, OF CHICAGO, ILLINOIS, A CORPORATION OF ILLINOIS.

WATER-CLOSET SEAT.

1,079,007.

Specification of Letters Patent.

Patented Nov. 18, 1913.

Application filed October 3, 1912. Serial No. 723,709.

To all whom it may concern:

Be it known that I, HERMAN M. HOELSCHER, a citizen of the United States, residing in Chicago, in the county of Cook and 5 State of Illinois, have invented a new and useful Improvements in Water-Closet Seats, of which the following is a specification.

This invention relates to improvements in water closet seats.

10 One object of the invention is to provide a water closet seat of rigid construction which is composed of material that is impervious and incorrodible, such as rubber, rubber compounds, cellulose, etc., and which 15 may be made plastic and molded.

Another object of the invention is to provide a water closet seat of the type above indicated, which will have embedded therein, a reinforcing or strengthening member of 20 metal which will be fully protected from possibility of corrosion from water or vapor, said strengthening or reinforcing member preventing the seat from liability of cracking or breaking from rough usage.

25 Other objects of the invention are to provide a water closet seat having a reinforcing or strengthening member embedded in the material forming the seat, which will have metal hinge lugs formed integrally with the 30 reinforcing or strengthening member and also a seat composed of rubber or equivalent material which is provided with an ornamental, polished, veneer surface.

The invention furthermore consists in improvements in the parts and in the novel combinations of the parts as herein shown, described or claimed.

Hitherto water closet seats have been made of metal but the same have been found objectionable for the reason that they soon corrode and feel cold to the body. In other instances, water closet seats have been made of other materials which could be molded but which are not as strong as metal and are 45 easily fractured or broken by rough handling. With my improvements the water closet seat possesses all the valuable properties inherent with the use of such moldable materials as rubber, rubber compounds, etc., 50 and has also the requisite strength to prevent liability of breakage and yet is free from the objections resulting from the use of metal.

In the drawing forming a part of this 55 specification, Figure 1 is a plan view of a

water closet seat embodying my improvements. Fig. 2 is a bottom plan view of the seat shown in Fig. 1. Fig. 3 is a longitudinal, vertical section taken on the line 3—3 of Fig. 1. Fig. 4 is a transverse section 60 taken on the line 4—4 of Fig. 1. Fig. 5 is an enlarged detail sectional view taken on the line 5—5 of Fig. 1, and Fig. 6 is a plan view showing my improvements embodied in what is commonly termed a "crescent" 65 seat.

In said drawing the seat is denoted generally by the reference A, and as shown, is substantially convex on its upper side and concave on the lower side, and may be composed of any substance which is impervious and non-corrodible, such as, for instance, rubber, rubber compounds, cellulose, etc., which are adapted to be made plastic and easily molded. Embedded in the rubber 70 or other material composing the seat, is a strengthening or stiffening member 11, which as shown in Fig. 1, extends entirely around the seat, and as shown in Figs. 1 to 3 inclusive, the hinge lugs 12 for the seat, 80 are made integrally with this strengthening member 11. In those instances where the seat is employed to automatically operate a flush valve, the flush-valve-operating lever or projection 13 may be also formed integral 85 with the stiffening or strengthening member 11, and in these instances connecting webs 14 are preferably employed between the hinge lugs 12 and the projection 13, which fit 90 against the back edge of the seat.

The seat is made convex-concave, as above described, for two reasons, first to reduce as much as possible the amount of rubber or other compound used, and second to keep the seat raised from the top rim 15 of the water 95 closet bowl in order to allow the free circulation of air beneath the seat and thereby prevent the collection of moisture or foul matter therebeneath.

In order to keep the seat raised or spaced 100 from the rim of the bowl, the seat is provided with rubber cushions 16 which are formed integrally with the material forming the seat, and in those cases where rubber or rubber compounds are employed, each cushion 105 is vulcanized to the main body of the seat, thus forming a seat having cushions attached thereto without any cracks or slots in which might collect moisture or other undesirable matter. As more clearly shown in 110

Fig. 5, the seat is provided on its upper surface with a veneer 17 which is composed of a better grade of rubber or rubber compound than that used in the body of the seat, and which may be highly polished and finished. In practice this veneer or outer surface is formed by lining the mold, in which the seat is molded, with a thin layer or veneer of rubber which will fuse with the rest of the material forming the seat during the molding operation.

In Fig. 6, the crescent seat B, which may be composed of rubber or other equivalent impervious, incorrodible substance has embedded therein, a crescent shaped strengthening or stiffening member 111 of metal. In this form of seat the embedded stiffening or strengthening member is highly desirable, since otherwise the ends of the arms forming the crescent are quite likely to become broken or cracked in use, because of the fact that there is no connecting portion therebetween as in the ordinary ring-like form of seat. In the construction shown in Fig. 6, the hinged lugs 112 are also preferably formed integral with the member 111, and a connecting web 114 is also provided between the hinge lugs 112 which fits the rear edge of the seat.

As shown in the drawings, the seat 10, is supported at a plurality of points, at the rear by the hinge connections, and at the front by the cushions 16, so that the seat is held spaced from the bowl 15 for the purpose hereinbefore described. The seat, being supported in this manner, will be subject to severe bending strains between the points of support by the weight of the user, and the stiffening or strengthening members 11 and 111 must be made strong enough to withstand these bending strains, and as shown in the drawings, these members 11 and 111 are

made of relatively large bars rectangular in cross section.

From the foregoing description it will be seen that I have provided a sanitary water closet seat which is free from undesirable cracks or joints such as are found in all wooden seats, and that the seat is thoroughly strengthened and stiffened substantially as rigidly as an all-metal seat, and yet which is free from all the disadvantages found in all-metal seats, and which is provided with a highly polished or finished surface.

Although I have herein shown and described what I now consider the preferred embodiments of my invention, yet it will be obvious to those skilled in the art, that various changes and modifications may be made in the details of construction without departing from the spirit of the invention, and all such changes and modifications are contemplated as come within the scope of the claims appended hereto.

I claim:—

1. A water closet seat of the character described, composed of rubber of an inferior grade and having a metal reinforcing member embedded therein, said seat being provided with an outer polished veneer surface of a better grade of rubber, substantially as specified.

2. A water closet seat of the character described, the main portion of which is composed of a plastic material of an inferior grade and having an outer, polished veneer surface of a better grade of plastic material, said seat being substantially concavo-convex in cross-section, substantially as specified.

HERMAN M. HOELSCHER.
